UNITED STATES PATENT OFFICE.

ARTHUR FORT EYCLES HYMER, OF NILES, MICHIGAN.

SWING.

Application filed December 28, 1921. Serial No. 525,302.

To all whom it may concern:

Be it known that I, ARTHUR FORT EYCLES HYMER, a citizen of the United States, and a resident of Niles, in the county of Berrien 5 and State of Michigan, have invented certain new and useful Improvements in Swings, of which the following is a specification.

My invention relates generally to swings, 10 more particularly to a child's swing, and it consists in the combinations, constructions and arrangements herein described and claimed.

An object of my invention is to provide a 15 child's swing of simplified construction which can be propelled readily by a child to swing in a desired manner.

A further object of my invention is to provide a swing which can be readily attached 20 to various fixed supports, as for instance to a ceiling wall, and which includes no parts which are likely to occasion injury to the child during the operation of the swing.

A still further object of my invention is 25 to provide a swing having means for holding the swing against movement laterally of the direction of its oscillation.

Other objects and advantages will be apparent from the following description and 30 the novel features of the invention will be particularly outlined in the appended claims.

My invention is illustrated in the accompanying drawings, forming a part of this application, in which:—

35 Fig. 1 is a side elevation showing a practical embodiment of the invention operatively applied, and

Fig. 2 is a front elevation of the structure shown in Fig. 1.

40 In carrying out my invention, I provide a seat 1 which may be of any desired form and made of any suitable material, preferably wood. A bar 2 which is secured to the under side of the seat 1 by any suitable fastening 45 means, extends longitudinally of the seat substantially intermediately of the width thereof and projects beyond the front end of the seat for a predetermined distance. The forward portion of the bar 2 is fashioned to 50 provide a twisted end portion 3 having spaced openings 4, formed therethrough. A propelling bar 5 is provided with a series of spaced openings 6 extending through the intermediate portion thereof. The propelling bar 5 is arranged relatively to the portion 3 so that selected openings 4 and 6 are

in registry and the propelling bar is then pivotally attached to the portion 3 through the agency of a bolt 7 projected through such registering openings. 60

The propelling bar 5 has an angular portion 8 at its upper end extending toward the seat. The angular portion 8 is provided at its end with a transverse handle bar 9.

The propelling bar 5 also has a twisted 65 portion 10 at its lower end bent to extend in the general direction of the seat 1. The numeral 11 denotes a foot plate or rest and a foot piece adapted to be positioned thereon is indicated at 12. The foot piece 12 has 70 a transversely extending channel 13 in its under side intermediately of its length adapted to receive the end of the portion 10. In consequence, the foot piece 12, the portion 10, and the foot plate or rest 11 may 75 be fastened together by means of a single bolt 14.

The foot rest 11 is additionally connected with the seat 1 through the agency of a pair of spaced flexible members 15—15 having 80 their upper ends attached to the front part of the seat adjacent to opposite corners thereof and their lower ends attached to the rear part of the foot rest at the corners of the latter. 85

A secondary propelling bar 16 is provided with a series of spaced openings 17 respectively substantially horizontally aligned with the corresponding opening 6 of the primary propelling bar 5, when both bars are in vertical position, as illustrated. A connecting bar 18 has openings at its opposite ends positioned in registry with selected corresponding openings 17 and 6 and is pivotally attached to both propelling bars through the 95 agency of bolts 19 and 20. The secondary propelling bar 16 is pivotally attached to the portion 3 by means of a bolt 21 projected through selected openings 17 and 4. With this arrangement, the connecting bar 18 will 100 be substantially parallel with the portion 3 when the secondary propelling bar 16 and the primary propelling bar 5 are arranged in parallelism, as illustrated.

A pair of flexible suspension members 105 22—22 have their lower ends secured to the back part of the seat 1 adjacent to the corners thereof and are provided at their other ends with hooks, such as indicated at 110 23—23, which may be connected with suitable elements carried by a fixed support as for instance the screw eyes 24—24 depend-

ing from a ceiling 25. Another flexible suspension member 26 is provided with a hook 27 at one end arranged to engage a screw eye 28 fastened in the ceiling 25 and is attached at its other end to the propelling bar 5 at the junction of the straight body of the propelling bar with the handle-carrying angular portion 8, as indicated at 29.

- From the foregoing description of the various parts of the device, the operation thereof may be readily understood. The suspension members described are adjusted so that the seat 1 will lie in a substantially horizontal plane when the swing is at rest.
- 15 A child seated on the swing places its feet upon the foot plate 11 in such manner that the foot piece 12 is pressed by the heel portions of the feet of the child. It will be obvious that an oscillatory or swinging motion will be imparted to the seat 1 when a pressure is exerted against the foot piece 12 and either or both of the handles 9 and 16' are pulled toward the operator. It will also be apparent that the extent of the oscillatory movement possible when a given force is applied, may be varied by varying the positions of the propelling bars with respect to the portion 3 to vary the ratios of the length of the portion of such bars extending above and below the portion 3. Moreover, the propelling bars 5 and 16 may be adjusted with respect to the portion 3 to position the foot plate or rest 11 and the handles 9 and 16' or at least one of such handles so that the swing is adapted for the use of children of various sizes.
- It is desirable that means be provided for preventing any appreciable sway or movement of the swing laterally of the main direction of its travel since small children are frequently thrown from a swing having a side sway or lateral motion. To this end, I provide means for exerting a tension on the flexible suspension members 22-22 to more effectively maintain the members in spaced parallel relation during the operation of the swing while permitting such movements thereof as are essential to the functioning of the swing in a desired manner.
- Such means comprises a frame having parallel horizontal members 30 and 31 connected at their ends by vertical members 32 and 33 and by intermediately crossed diagonal members 34 and 35, the latter serving as struts and assuring the provision of a frame of sufficient strength and durability for the purpose intended. Hooks, indicated at 36, 37, 38 and 39 respectively, extend from the opposite ends of the diagonal struts in substantial alinement therewith. The hooks at the upper ends of the diagonal struts are arranged to engage rings 40-40 carried by the flexible suspension members 22-22 at predetermined distances from the upper ends thereof. The

hooks at the lower end of the frame embrace the suspension members 22-22. The horizontal members 30 and 31 of the frame have a length slightly greater than the normal distance between the suspension members 22-22, whereby the latter are slightly spread intermediately when the frame is applied in the manner illustrated and are thus placed under sufficient tension to prevent the sway of the seat from side to side during the oscillation thereof.

Obviously, my invention is susceptible of embodiment in forms varying in detail from that described in the foregoing and illustrated in the accompanying drawings. I therefore consider as my own, all adaptations and modifications of the form of the device herein described and illustrated which fall within the spirit and scope of the invention as indicated by the foregoing disclosure and by the appended claims.

I claim:

1. In a swing, a pair of normally parallel spaced flexible suspension members, and means for exerting tension upon said flexible members to limit the movement of such members relatively to each other, said means comprising a substantially rigid frame having a length slightly greater than the normal distance between said suspension members, said frame having means at the ends thereof for engaging the suspension members whereby the engaged portions of the latter are spread apart slightly.

2. A swing comprising a seat, a pair of flexible suspension members connecting with the rear portion of the seat at spaced-apart points and adapted for connection with a fixed support, a bar secured to said seat and having a portion extending along the longitudinal axis of the seat for a predetermined distance in advance of the forward end of the seat, a propelling bar pivotally and adjustably attached to said extending portion intermediately of the length of the propelling bar, the latter being provided with rearwardly extending angular portions at its ends, a handle carried by the angular portion of the propelling bar at the upper end of the latter, a foot rest attached to the lower end of the latter, and means for swingingly suspending the propelling bar from the fixed support.

3. A swing comprising a seat, a pair of flexible suspension members connecting with the rear portion of the seat at spaced-apart points and adapted for connection with a fixed support, a bar secured to said seat and having a portion extending along the longitudinal axis of the seat for a predetermined distance in advance of the forward end of the seat, a propelling bar pivotally and adjustably attached to said extending portion intermediately of the length of the propel-

ling bar, the latter being provided with rearwardly extending angular portions at its ends, a handle carried by the angular portion of the propelling bar at the upper end 5 of the latter, a foot rest attached to the angular portion of the propelling bar at the lower end of the latter, means for swingingly suspending the propelling bar from the fixed support, and flexible means connecting the foot rest with the seat at the 10 forward end of the latter.

4. A swing comprising a seat, a pair of flexible suspension members connected with the rear portion of the seat at spaced apart 15 points and adapted for connection with a fixed support, a bar secured on said seat and having a portion projecting in advance of the forward end of the latter, a propelling bar intermediately pivoted on the projecting 20 portion of the first bar, said propelling bar having a rearwardly extending handle carrying angular portion at its upper end and a rearwardly extending foot rest carrying portion at its lower end, a flexible sus- 25 pension member connected with said propelling bar at the junction of the body thereof with its upper angular portion and being adapted for connection with the fixed sup- 30 port to position the seat in a desired plane, and auxiliary propelling means having con-

nexion with said first named propelling bar and with the extending portion of the fixed bar.

5. A swing comprising a seat, a pair of flexible suspension members connected with the rear portion of the seat at spaced apart 35 points and adapted for connection with a fixed support, a bar secured on said seat and having a portion projecting in advance of the forward end of the latter, a propelling bar intermediately pivoted on the projecting portion of the first bar, said propelling bar having a rearwardly extending handle carrying angular portion at its upper end and a rearwardly extending foot rest carrying 40 portion at its lower end, a flexible suspension member connected with said propelling bar at the junction of the body thereof with its upper angular portion and being adapted for connection with the fixed support to position the seat in a desired plane, a secondary 45 propelling bar adjustably and pivotally attached to said extending portion of the first bar and being provided with a handle at its free end, and an adjustably and pivotally 50 attached member connecting the secondary propelling bar with the first named propelling bar. 55

ARTHUR FORT EYCLES HYMER.
